FOLDING TABLE

Cornell Flagstad, Minneapolis, Minn.

Application July 22, 1935, Serial No. 32,509

5 Claims. (Cl. 311—80)

This invention relates to folding tables particularly of the one piece top type used for card playing, and the primary object is to provide a folding leg structure for such a table that will not only serve to support the table in either set up or collapsed condition, but is so designed that it will be efficient and practical in construction, comparatively simple and sturdy in design, and can be set up and folded together with a minimum amount of effort. Other and more specific objects will be disclosed in the following specification, reference being made to the accompanying drawings, wherein various forms of the invention are illustrated, and in which—

15 Fig. 1 is an elevation of a preferred form of the table, as seen from one side thereof, and with fractional portions broken away for purpose of illustration.

Fig. 2 is a sectional plan view on the line 2—2 in Fig. 1.

20 Fig. 3 is a plan elevation of the table shown in Fig. 1 in its collapsed condition and with the lower leg brace locks omitted.

Fig. 4 is an edge elevation of the table as seen from the left in Fig. 3.

25 Fig. 5 is an enlarged detail section on the line 5—5 in Fig. 3.

Fig. 6 is a bottom perspective elevation of a modified form of table in partly collapsed condition, and with the bottom ends of the legs broken away.

30 Fig. 7 is an enlarged detail view of a modified form of latching cleat, as on the line 7—7 in Fig. 6.

Fig. 8 is an elevation corresponding to Fig. 3 but showing a modified design permitting a swiveling action of the table top.

35 Fig. 9 is an enlarged detail section on the line 9—9 in Fig. 8, but with the table top swung to its horizontal position.

40 Fig. 10 is an enlarged detail section of one of the primary leg frame locks used in the table of Fig. 8, and on the line 10—10 thereof.

Fig. 11 is an enlarged detail section through 45 one of the secondary leg frame locks, as on the line 11—11 in Fig. 8.

Fig. 12 is an elevation of a further modification of table structure, in collapsed condition.

50 Fig. 13 is an enlarged detail section through the table top, as on line 13—13 in Fig. 12, but showing the top in its set up or horizontal position and adjacent leg frame structures in opened out and top supporting positions.

55 Referring to the drawings more particularly and by reference characters, A designates a table

top, and B and C respectively designate primary and secondary leg frame structures for supporting the top. The top proper may be constructed in various designs but is here shown as comprising a flat upper sheet 14 of wood, fibre or metal, and reinforced by marginal strips 15 and diagonally disposed crossed strips 16, all secured to the underside of sheet 14, leaving the upper face smooth and level. The top is preferably of square form, although as indicated in Figs. 1, 3, 10 5 4, 6, and 12, the corners are shown as cut away to give a neater appearance and reduce the storage width space required when the table is not in use. In Figs. 6 and 7 modified top and leg frame units are respectively designated as 15 A1, B1, and C1; in the form shown in Figs. 8—11 they are designated as A2, B2, and C2; and in the modification of Figs. 12 and 13 the corresponding parts are designated by A3, B3, and C3.

In the form of the invention as disclosed in 20 Figs. 1 to 5, inclusive, the primary leg frame B is made up of piping or tubular material, and comprises a horizontal cross bar 17, the opposite ends of which have integral leg extensions 18. The bar 17 is pivotally secured to one of the 25 cross strips 16 of the table top by means of strap hinges 19, which permit the top to be swung from the horizontal position shown in Fig. 1 to the vertical position indicated in Figs. 3 and 4. The lower ends of the legs 18 are preferably 30 spread out so as to give better floor support to the top corner portions thereabove.

Intermediate the lower and upper ends of the 35 frame legs 18 they are rigidly connected by a tubular cross bar 20, the ends of which are preferably welded to the leg bars so as to rigidly and permanently connect them. The secondary leg frame C in the present instance is made up of two sections which are pivotally connected with respect to each other and with respect to the horizontal bars 17 and 20 of the primary leg frame, by pivot pins 21 and 22, respectively. These secondary leg frame sections each 40 comprise a leg bar 23 of substantially the same formation as the legs 18, and the upper ends of these 45 legs 23 have integral, horizontal extensions 24 which connect at the pivot pins 21. Immediately adjacent to the cross bar 20, and in a horizontal plane parallel therewith, the legs 23 are provided with brace bars 25 which connect at 50 the pivot pin 22.

The foregoing construction permits the two 55 sections of the leg frame C to be moved into the full line position shown in Fig. 2, at which time they are at right angles with respect to the leg 55

frame B, and to be swung from this normal or operative position into the inactive or collapsed condition indicated by the dotted lines 26 in Fig. 2.

To the end that the two leg frames may be folded into as small a space as possible, the cross bar 20 of the frame B is attached to one side of one of the legs 18, and to the opposite side of the other leg 18, thereby permitting the legs 10 of the frame C to be moved into the same plane as that of the legs 18, it being understood that the legs 23 are slightly closer than the legs 18 so that they may move into position immediately within the limits of the latter, as clearly shown 15 in Figs. 2 and 3.

When the table is to be set up into operative position, the top A is first swung into its horizontal position, and the two sections of the leg frame C are then pulled out either singly or simultaneously to the right angular position indicated in Fig. 2, at which time they will be disposed directly under the cross strip 16, which is at right angles to the other strip 16 directly above the leg frame B. In order that the two sections of the leg frame C may properly and rigidly support the top, and also be releasably secured in position so as to prevent accidental displacement, I provide a pair of latch devices designated generally by the letter D, and one of which is shown in detail in Fig. 5. Each of these latch devices comprises a block or cleat 27, notched out to receive the adjacent cross strip 16, and rigidly secured under the table top. The block extends sufficiently below the strip 16 so as to span the vertical space between the strip and the frame bars 24 occasioned by the cross bar 17. And the blocks 27 are so arranged that they rest directly upon the bars 24 to give a positive support for the parts of the top disposed laterally with respect to the vertical plane of the frame B. The blocks 27 are preferably provided with inclined edge surfaces 28 to guide the leg movements, and the leg bars 24 are releasably secured in their operative positions by engaging in a notch 29 of a lever 30 pivoted as at 31 in a slot 32 of the block. A spring 33 tends to hold the latch 30 in frictional engagement with the frame bar 24, and a slot and pin arrangement 34 serves to limit the movement of the latch.

It will now be seen that when the leg frame bar 24 is moved into operative position the latch 30 will yield, under the action of the spring 33, to permit the bar to move into releasable engagement in the notch 29, but that the latch 30 will give sufficiently so as to not interfere with the direct supporting contact as between the block 27 and the frame bar 24. The outer end of the latch 30 is conveniently provided with a lateral extension or tongue 35 which can be pressed upwardly 50 when it is desired to release the frame bar 24 from the notch 29, as when the table is to be collapsed and set away out of use.

As an additional means of interlocking and releasably bracing the leg frames, and this device 65 may be used in any of the modifications shown, I provide (Figs. 1 and 2) a pair of right angularly bent, heavy wire braces 36 having loops or eyes 37 at their ends for encircling the cross bar 20 at spaced points at opposite sides of the pivot pin 70 22, so that the braces may be swung toward and away from the bars 25 of leg frame C. Collars 38 (Fig. 2) may be employed to prevent sliding movement of the braces on bar 20. Intermediate their ends the braces have integral U-shaped loops or jaws 39 adapted to snap down into inter-

locking relationship with the bars 25 to brace them with respect to the bar 20. These braces must of course be released before the leg frames can again be folded together.

In the modification shown in Figs. 6 and 7, the leg frame B1 is identical with the previously described leg frame B, but the secondary leg frame C1, in preference to being sectionally formed, is made in one solid integral unit, with upper and lower cross bars 40 and 41 which pivot to the bars 17 and 20 as at 42 and 43, respectively. In this case the table top A1 must be moved entirely into its horizontal position, before the leg frames can be unfolded; but when that position is reached the frame C1 is swung out to the right angular position with respect to the frame B1 and is releasably secured by latch blocks D1 which correspond generally to the blocks D but do not include any moving parts. Thus the blocks D1 are rigidly attached to the under side of the table top A1 and have notches 44 to receive opposite end portions of the cross bar 40. Projecting shoulders 45 adjacent the notches prevent the leg frame C1 from being swung beyond its normal supporting position. The parts are so arranged that when the frame C1 is moved into its operative position the bar 40 will snap into engagement in the notches 44, this releasable snapping engagement being effected by the resiliency of the table top proper. The notches 44 are sufficiently shallow so that when it is desired to fold up the table the bar 40 can be pulled laterally out of engagement with the notches.

In the table structure illustrated in Figs. 8 to 11, inclusive, the table top A2 is mounted not only for tilting action from vertical to horizontal positions, as in the previously described forms, but also has a swiveling connection with respect to the leg frames so that it can be turned from the angular position indicated by dotted lines in Fig. 8 to the full line position when it is to be stored, and in which condition it will of course require considerable less storage space. To this end I provide the upper bar 46 of the primary frame B2 with a collar 47 in which the bar may rotate, but which collar is in turn pivotally secured to a plate 48 as by a screw 49 so that the collar can turn on an axis perpendicular to the plane of the table top, the plate 48 being secured to the strips 16 as by screws or pins 50. The primary leg frame B2 further includes legs 51 and a lower cross bar 52 similar to the corresponding elements previously described in other forms of the table structure.

The secondary leg frame C2 may be of unitary construction, as shown in Figs. 6 and 12, but is here shown as being sectionally formed substantially as in Figs. 1 and 3, and these sections are connected to the primary leg frame by pivots 53 and 54. The two upper pivots 54 are necessarily spaced one at each side of the collar 47, and can therefore not be in direct axial alignment with the pivot pin 53. It is found, however, that there is sufficient resiliency in the parts to permit the secondary leg sections to be swung without any binding action or noticeable distortion.

One of the bracing strips 16 is provided at opposite sides of the plate 48 with a pair of spring clips 55 which open in opposite directions and are adapted to receive opposite ends of the frame bar 46 when the table top is turned into the angular position indicated by the dotted lines in Fig. 8. When the table top A2 is then tilted to its horizontal position the sections of the secondary leg frame C2 can be pulled out

to releasably engage a pair of latch devices D2, shown in detail in Figs. 9 and 11. Each of these latch devices comprises a wedge shaped block 56 secured to the table top adjacent opposite sides of the strip 16 which is at right angles to the strip which supports the clips 55. Each block 56 has a hook 57, preferably formed of strapped metal and secured upon the inclined face of the block 56 so as to guide the upper arms 58 of the secondary leg frame. The hook 57 is not necessarily a spring clip such as 55, but primarily constitutes a hook for receiving and limiting the swinging movement of the bar 58 which it is to receive. The bar 58 is releasably secured in the hook by a wire spring 59 which operates in a slot 60 in the block 56 where it is anchored by pins 61, and has a hump 62 which projects through a small slot 63 in the hook member 57.

20 In the modification shown in Figs. 12 and 13, the primary leg frame B3 comprises legs 64 rigidly connected by cross bars 65 and 66, and the secondary leg frame C3 includes legs 67 connected by upper and lower cross bars 68 and 69, which cross bars are respectively pivoted to the cross bars 65 and 66 as at 70 and 71. In this instance, however, the legs 64 are flattened at their upper ends, and pivotally connected as by pintles 72 to hinge brackets 73 secured to one 25 of the table top strips 16. In this case also the bar 65 of the primary frame is not disposed adjacent the strip 16, but is slightly spaced therefrom so that the secondary leg frame bar 68 will be disposed between the table top and the bar 65. When the top A3 is now turned to its 30 horizontal position the secondary leg frame C3 can be swung to a position at right angles with respect to frame B3, at which time the bar 68 is moved into supporting position immediately 35 under the cross strip 16 which is at right angles to the cross strip 16 that attaches to the leg frame B3. The under side of the table top is provided with a pair of spring hooks or catches 40 45 74 adapted to receive and releasably secure the secondary leg frame in its supporting position.

It is understood that suitable modifications may be made in the structure as disclosed, provided such modifications come within the spirit and scope of the appended claims. Having now 50 therefore fully illustrated and described my invention, what I claim to be new and desire to protect by Letters Patent is:

1. In a folding table a substantially square top, a pair of intersecting leg frames pivotally connected and normally disposed in vertical planes diagonally under the top, means connect-

ing the top to one of the frames and permitting tilting of the top into a vertical plane in parallelism with such frame and permitting turning of the top on an axis perpendicular to its plane, and means for releasably securing the frames 5 and top in set up position, one of said frames being sectionally formed and pivotally connected to permit independent or simultaneous movement of the sections with respect to the other frame.

2. In a folding table a substantially square top, a pair of intersecting leg frames pivotally connected and normally disposed in vertical planes diagonally under the top, means connecting the top to one of the frames and permitting tilting of the top on an axis in the plane of such frame and into a vertical plane parallel with the frame, and permitting turning of the top on an axis perpendicular to its plane, means operative upon such turning of the top to releasably secure it to one of the frames, and other means for releasably securing the top with respect to the other frame.

3. A folding table comprising a top member, a pair of intersecting and pivotally connected 25 leg frames for supporting the top member and disposed thereunder in vertical, intersecting planes, said frames each including a pair of leg members connected by a cross bar, and an angularly formed brace member pivotally secured at opposite ends to one leg frame and with an intermediate portion releasably engageable with the cross bar of the other leg frame.

4. A folding table comprising a top member, a pair of intersecting and pivotally connected 35 leg frames for supporting the top member and disposed thereunder in vertical, intersecting planes, said frames each including a pair of leg members connected by a cross bar, and a brace member swingably secured at its ends to one 40 of the leg frames and having a U-shaped portion releasably engageable with a portion of the other leg frame.

5. A folding table comprising a top member, a pair of intersecting and pivotally connected 45 leg frames for supporting the top member and disposed thereunder in vertical, intersecting planes, said frames each including a pair of leg members connected by a cross bar, and a pair of brace members hingedly secured at opposite 50 ends to one of the leg frames and having intermediate portions releasably engageable with the other leg frame to brace the leg frames with respect to each other.

CORNELL FLAGSTAD.
